A43B 23/07; A43B 23/45; A43B 13/10;
A43B 13/12; A43B 13/125; A43B
13/186; A43B 21/00; A43B 21/02; A43B

FIG. 1 is a front perspective view of our shoe, according to
our design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines shown in the drawings represent portions
of the shoe that form no part of the claimed design. The

(Continued)

longer, even-length broken lines within the shaded area of the shoe upper represent stitching that forms part of the claimed design. Areas of the design shown with a stipple fill illustrate a contrast in appearance.

1 Claim, 6 Drawing Sheets
